REFRIGERATING APPARATUS

Harry F. Smith, Dayton, Ohio, assignor to General Motors Corporation, Dayton, Ohio, a corporation of Delaware

Application March 31, 1934, Serial No. 718,315

18 Claims. (Cl. 62—117)

This invention relates to refrigeration and more particularly to the conditioning of air.

There is among the objects of this invention to provide a method and apparatus for conditioning 5 air in which the refrigerant liquefying unit may be operated at varying capacities or where driving power therefor is available only periodically and in which an efficient holdover is provided as an aid in conditioning the air while the refriger- 10 ant liquefying unit lacks sufficient capacity. More specifically this invention is applicable to moving vehicles such as railway cars or the like where the refrigerant liquefying unit is driven by energy generated during the motion of the car and 15 where the liquefying capacity of the unit or the availability of driving power varies due to variations in the motion of the car.

Further objects and advantages of the present invention will be apparent from the following description reference being had to the accompanying drawings, wherein a preferred form of the present invention is clearly shown.

In the drawings:

Fig. 1 is a vertical cross-sectional view, some- 25 what diagrammatic, of an apparatus embodying my invention;

Fig. 2 is a cross-sectional view taken along the line 2—2 of Fig. 1;

Fig. 3 is a horizontal diagrammatic view of a 30 car showing a type of air flow which may be used;

Fig. 4 is a vertical cross-sectional view some- 35 what similar to Fig. 1 but showing a slightly modified form of the invention.

In practicing my invention, the air to be conditioned for the enclosure 10 of the car or the like is brought into thermal contact with the air conditioning apparatus and is then discharged into the compartment 10. If desired, two air conditioning units 11 and 12, substantially identical but 40 symmetrically arranged are placed at opposite ends of the car in the upper portion thereof to discharge oppositely directed streams of air 13 and 14 above the heads of persons seated in the seats 15 of the car. Any arrangement for circulating 45 the air may be used, and this particular one is shown by way of example.

The apparatus for conditioning air may include 50 a refrigerating system comprising a refrigerant evaporator 16 and a refrigerant liquefying unit 17 operatively connected with each other so that liquid refrigerant is circulated through the line 18 to the evaporator where the refrigerant is evaporated and returns through the line 19. A suitable 55 expansion valve 20 is provided in the line 18 which is controlled by a thermostatic bulb 21 placed at

the outlet of the evaporator and which tends to throttle the valve 20 when the outlet pipe is cooled below a predetermined temperature. This tends to prevent "frost-back" in the suction line. The valve 20 is provided with an automatic control as 5 is well known, which is set to maintain a refrigerant pressure in the evaporator corresponding to a temperature slightly above 32° F. as long as the thermostatic bulb does not throttle the valve further. When the evaporator becomes sufficient- 10 ly filled with liquid refrigerant so that refrigerating tends to occur in the line 18, then the thermostatic bulb 21 throttles the valve 20 and reduces the amount of liquid refrigerant entering the evaporator. If desired, an evaporated re- 15 frigerant throttling valve 22 is placed in the suction line which is controlled by a thermostatic bulb 23 so that if "frost-back" occurs in pipe 18, notwithstanding the operation of the valve 20, then the valve 22 is throttled and thus reduces 20 the suction effect of the liquefying unit on the evaporator.

The air is caused to flow over the evaporator 16 by means of a blower or fan 24 having its in- 25 take connected with the compartment 10, or with the atmosphere outside of the car, or both. The air circulating capacity of fan 24 and the effective refrigerating area of the evaporator 16 are so proportioned with the various valves in the sys- 30 tem, so that when the air at summer temperature flows over the evaporator, the surfaces thereof are near but above 32° F.

The refrigerant liquefying unit 17 is driven by energy generated by the motion of the car. The driving means therefore may be either directly 35 connected to a wheel of the car, or it may be driven by an electric motor supplied with electricity generated by a generator driven by the wheel. In the particular embodiment shown in Fig. 1, the unit is driven directly by the wheel 25 of 40 the car. Thus a belt drive, or similar drive, 26 connects the wheel 25 with the pulley 27 which in turn is connected by a belt drive 28 with the compressor 29 of the liquefying unit. The refrigerant compressed by the compressor 29 is 45 discharged into the condenser 30, which may be either air cooled or water cooled, and the liquefied refrigerant is delivered to the receiver 31, from whence it flows through the line 18 to the evaporator. The refrigerant liquefying unit 17 thus has 50 imparted thereto periods of excess refrigerating capacity and periods of insufficient refrigerating capacity when the car travels at low speeds or when it stops entirely. The evaporator 16 has therefore likewise periods of excess refrigerating 55

capacity and periods of insufficient capacity with regard to the refrigerant flow therethrough. If desired, the drive between the wheel 25 and the compressor may include a constant speed automatic transmission which tends to drive the compressor at substantially constant speed regardless of the speed of the car.

A holdover system is placed in thermal exchange relation with the refrigerating system and 10 more specifically with the evaporator 16 thereof. To this end, a volatile fluid such as water is placed in a closed holdover space from which air has been removed as completely as possible. This holdover space may include a thermal exchange 15 holdover phase changing portion 32 in thermal exchange relationship with the evaporator and evaporative holdover phase changing portion 33, properly insulated by insulation 34 and placed underneath the floor of the car.

20 The portion 32 may be placed in thermal exchange relationship with the evaporator through the medium of fins 35 through which the coils 36 at evaporator 16 pass. The upper ends of fins 35 are bent at 37 and are soldered or brazed to the 25 floor 38 of the portion or chamber 32 of the holdover system. The evaporative portion 33 may be provided with evaporating surfaces or pads 39 and the two portions may be connected by a pipe 40 suitably insulated as indicated.

30 While the car is traveling at normal or high speeds, air is forced through the evaporator by the motor driven fan 24 with the openings 41 in fully opened condition. Normally such operation causes the refrigerating surfaces to be 35 maintained near but above 32° F. After a certain period of operation the temperature in the compartment 10 usually is reduced below a pre-determined limit at which time the thermostatic bulb 42, acting through the bellows 43 actuates 40 the shutters 44 to close openings 41 and open openings 41a to throttle the flow of air over the evaporator and thus reduce the thermal exchange relationship between the air and the evaporator. The air circulated by the fan 24 then flows 45 through the bypass 45 substantially without any cooling action from the evaporator. Under these conditions, the refrigerating capacity of the system is such that the temperature of the refrigerating surfaces of evaporator 16 falls below 32° F. 50 because no heat from the air is applied thereto. This in turn reduces the temperature of the surfaces in the portions 32 below the freezing temperature of water vapor therein which thus changes phase on the inner surfaces of the 55 portion 32. This change of phase of water vapor is accompanied by a transfer of heat from the holdover fluid to the evaporator 16. Simultaneously water vapor is formed in the evaporative portion 33 to replace the vapor removed by 60 change of phase in 32. As this action continues, the water in the portion 33 is frozen on the evaporative surface or pads 39, and thus a refrigerating holdover capacity is built. When the temperature of the compartment 10 rises, either be- 65 cause the refrigerating capacity of refrigerating systems is decreased due to a change in the motion of the car, or because the heat infiltration into the car raises the temperature thereof, the thermostatic bulb 42 opens the shutter 41 and 70 closes the bypass 45 so that air is once more forced over the evaporator 16. When this occurs, the air is cooled either through the action of the refrigerating system or through a change of phase in the holdover fluid, or both. Thus if 75 the car is stopped, heat travels from the air

through the fins 35 to the holdover frozen in the portion 32. As this holdover melts and absorbs heat from the air, the vapors are then driven downwardly through the pipe 40 to the portion 33 where they are condensed by the melting of ice on surfaces 39. The cooling action of the holdover thus continues as long as any ice remains in the holdover system. The total holdover capacity of the system is made sufficient to cool the car during normal stops at stations. 10

If desired, a motor 50 is provided with a suitable clutch which connects the motor and disconnects the wheel drive to drive the compressor 29 with current from the station when the car stops for abnormally long periods of time such as at terminals or the like. The motor 50 is started and stopped by means of a switch 51 responsive to back pressures in line 19 or to temperatures in the room as preferred.

In the modification shown in Fig. 4 the parts 20 which are similarly numbered are made substantially the same as in Fig. 1, with the exception that two pipes 40' and 40'' connect the portions 32 and 33 of the holdover system. The holdover system is not operated at a vacuum as in Fig. 1 25 but an inert gas, such as air, is permitted to remain therein so that the holdover system internal pressure is substantially equal to atmospheric pressure. A small blower 52 is placed in the pipe 40' and is driven by motor 53 under 30 control of a switch 54. The fan or blower 52 circulates the air through the holdover system and thus causes the water vapor to be circulated with the air between the two portions of 32 and 33. 35

While the form of embodiment of the invention as herein disclosed, constitutes a preferred form, it is to be understood that other forms might be adopted, all coming within the scope of the claims which follow.

What is claimed is as follows:

1. An air conditioning apparatus comprising a refrigerating system including a refrigerant evaporator and a refrigerant liquefying unit in operative relationship, means for selectively placing said evaporator in and out of thermal exchange relationship with the air to be conditioned, a holdover system in thermal exchange relationship with said evaporator, said holdover system including a thermal exchange holdover phase changing portion and an evaporative holdover phase changing portion connected to said first named portion, arranged to cause said holdover to add heat to said evaporator and remove heat from said evaporative holdover phase changing portion during periods of excess capacity of said refrigerating system and to remove heat from the air during periods of insufficient capacity of said refrigerating system. 50

2. An air conditioning apparatus comprising a refrigerating system including a refrigerant evaporator and a refrigerant liquefying unit in operative relationship, means for selectively placing said evaporator in and out of thermal exchange relationship with the air to be conditioned, a holdover system in thermal exchange relationship with said evaporator, said holdover system including a thermal exchange holdover freezing portion and an evaporative holdover freezing portion connected to said first named portion, arranged to cause said holdover to add heat to said evaporator and remove heat from said evaporative holdover freezing portion during periods of excess capacity of said refrigerating system and to remove heat from the air 65

during periods of insufficient capacity of said refrigerating system.

3. An air conditioning apparatus comprising a refrigerating system including a refrigerant evaporator and a refrigerant liquefying unit in operative relationship, means for selectively placing said evaporator in and out of thermal exchange relationship with the air to be conditioned, a holdover system in thermal exchange relationship with said evaporator, said holdover system including a thermal exchange holdover phase changing chamber in thermal exchange with said evaporator and an evaporative holdover phase changing chamber connected to said first named chamber, means for increasing and decreasing the air thermal exchange relationship between the air and said evaporator while said refrigerating system is operating, said holdover system being arranged to add heat to said evaporator from said evaporative holdover phase changing chamber when said air thermal exchange relationship is decreasing and to remove heat from said air when the capacity of said refrigerating system is insufficient to condition said air.

4. An air conditioning apparatus comprising a refrigerating system including a refrigerant evaporator in thermal exchange relationship with said air and a refrigerant liquefying unit operatively connected to said evaporator, means for imparting to said system periods of excess refrigerating capacity and periods of insufficient refrigerating capacity, a holdover system in thermal exchange relationship with said evaporator, said holdover system including a thermal exchange holdover phase changing portion and an evaporative holdover phase changing portion connected to said first named portion, the relationship between said systems being such that heat is removed from said evaporative holdover phase changing portion with a change of phase in said holdover during said periods of excess refrigerating capacity.

5. An air conditioning apparatus comprising a refrigerating system including a refrigerant evaporator in thermal exchange relationship with said air and a refrigerant liquefying unit operatively connected to said evaporator, means for imparting to said system periods of excess refrigerating capacity and periods of insufficient refrigerating capacity, means for increasing and decreasing the air thermal exchange relationship between the air and said evaporator during said periods of excess refrigerating capacity, a holdover system in thermal exchange relationship with said evaporator, said holdover system including a thermal exchange holdover phase changing portion and an evaporative holdover phase changing portion connected to said first named portion, the relationship between said systems being such that heat is removed from said evaporative holdover phase changing portion with a change of phase in said holdover during said periods of excess refrigerating capacity, while said air thermal exchange relationship is decreasing and to remove heat from said air during said periods of insufficient refrigerating capacity.

6. A car, an air conditioning apparatus for said car, a refrigerating system including a refrigerant evaporator in thermal exchange relationship with said air and a refrigerant liquefying unit operatively connected to said evaporator, means for operating said refrigerant liquefying unit by energy generated during motion

of said car, means for throttling the cooling effect of said evaporator below the refrigerating capacity of said system while said car is in motion, a holdover system including a volatile fluid and means for condensing vapor of said fluid while said evaporator is throttled, and means for evaporating said condensed fluid and cooling said air while said refrigerating system is below refrigerating capacity because of insufficient motion of said car.

7. A car, an air conditioning apparatus for said car, a refrigerating system including a refrigerant evaporator in thermal exchange relationship with said air and a refrigerant liquefying unit operatively connected to said evaporator, means for operating said refrigerant liquefying unit by energy generated during motion of said car, means for throttling the cooling effect of said evaporator below the refrigerating capacity of said system while said car is in motion, a holdover system including a volatile fluid and means for condensing vapor of said fluid while said evaporator is throttled, an inert gas in said holdover system and means for evaporating said condensed fluid and cooling said air while said refrigerating system is below refrigerating capacity because of insufficient motion of said car.

8. A car, an air conditioning apparatus for said car, a refrigerating system including a refrigerant evaporator in thermal exchange relationship with said air and a refrigerant liquefying unit operatively connected to said evaporator, means for operating said refrigerant liquefying unit by energy generated during motion of said car, means for throttling the cooling effect of said evaporator below the refrigerating capacity of said system while said car is in motion, a holdover system including a volatile fluid and means for condensing vapor of said fluid while said evaporator is throttled, an inert gas in said holdover system means for positively circulating said gas and means for evaporating said condensed fluid and cooling said air while said refrigerating system is below refrigerating capacity because of insufficient motion of said car.

9. An air conditioning apparatus comprising an evaporator and a refrigerant liquefying unit operatively connected thereto, means drivingly connected to said liquefying unit, a fan circulating air over said evaporator, means throttling the cooling action of said evaporator on said air, a closed fluid holdover system having a heat exchange portion in heat exchange with said evaporator and an insulated evaporative portion and in which heat exchange portion said fluid changes phase with loss of heat to said evaporator when said throttling means is operative and changes phase with absorption of heat when said liquefying unit lacks sufficient refrigerating capacity and in which evaporative portion said fluid changes phase to supply and withdraw fluid from said other portion.

10. The method of conditioning air or the like which comprises thermally exchanging heat between said air and an evaporating refrigerant, reliquefying said refrigerant for re-use at rates above and below the requirements for conditioning said air, periodically throttling the exchange of heat between said air and refrigerant and simultaneously changing two phases of a volatile fluid including a vapor phase change by the removal of heat from said fluid into said refrigerant, and changing the phases of said fluid with addition of heat from said air to said fluid while

said reliquefying rate is below the requirements for conditioning said air.

11. An air conditioning apparatus comprising a refrigerating system including a refrigerant evaporator and a refrigerant liquefying unit in operative relationship, means for selectively placing said evaporator in and out of thermal exchange relationship with the air to be conditioned, a holdover system in thermal exchange relationship with said evaporator, said holdover system including a substance to be frozen by the change in vapor phase of said substance during periods of excess capacity of said refrigerating system and melted during periods of insufficient capacity of said refrigerating system.
12. An air conditioning apparatus comprising a primary refrigerating system and a holdover system, said primary refrigerating system including means for cooling air and for cooling a first portion of said holdover system, said holdover system including said first portion and a second portion below said first portion and means for flowing a volatile secondary refrigerant between said portions, said volatile secondary refrigerant changing at least its vapor phase in said first portion by introducing heat into said primary refrigerating system during periods of activity of said primary refrigerating system and by removing heat from air during periods of less activity of said primary refrigerating system, said volatile secondary refrigerant changing at least its vapor phase in said second portion substantially concurrently with the vapor phase changes in said first portion.

13. A refrigerating apparatus comprising means to be cooled, a primary refrigerating system and a holdover system, said primary refrigerating system including a cooling member for said means to be cooled, said holdover system including a first portion to be cooled by said primary refrigerating system, a second portion connected to said first portion and means for flowing a volatile secondary refrigerant between said portions, said primary refrigerating system having periods of excess refrigerating capacity and periods of insufficient refrigerating capacity, said secondary refrigerant changing at least its vapor phase in said first portion and to its solid phase

in said second portion by introducing heat into said primary refrigerating system during said periods of excess refrigerating capacity and changing at least to its vapor phase in said first portion and from its solid phase in said second portion during said periods of insufficient refrigerating capacity.

14. An apparatus in accordance with claim 13, in which said primary refrigerating system is controlled in accordance with conditions of said means to be cooled.

15. An apparatus in accordance with claim 13, in which said holdover system is controlled in accordance with conditions of said means to be cooled.

16. In combination, a first evaporator, a second evaporator, heat radiating fins each in thermal exchange relationship with both of said evaporators, means for supplying refrigerant to said first evaporator, means for independently supplying refrigerant to said second evaporator, and means for circulating air to be conditioned over said heat radiating fins whereby either evaporator may cool said air independently of the other evaporator.

17. In combination, a first evaporator, a second evaporator, heat radiating fins each in thermal exchange relationship with both of said evaporators, means for supplying refrigerant to said first evaporator, means for independently supplying refrigerant to said second evaporator, means for circulating air to be conditioned over said heat radiating fins, and means for controlling the flow of air over said heat radiating fins whereby either evaporator may cool said air independently of the other evaporator.

18. In combination, a first heat exchange member, a second heat exchange member, heat exchange fins each in thermal exchange relationship with both of said members, means for supplying an attemperating medium to said first member, means for independently supplying an attemperating medium to said second member, and means for circulating air to be conditioned over said heat exchange fins whereby either of said heat exchange members may condition air independently of the other heat exchange member.

HARRY F. SMITH.
